Lester Umberger, La Crosse, Wis.

Application April 30, 1956, Serial No. 581,564

3 Claims. (Cl. 256—19)

This invention relates to fences, and while the invention is more specifically intended for use where the posts are constructed of concrete and the bars are constructed of wood, it should be understood that the fence may be constructed of any suitable material. By making the posts of concrete or similar material, the structure is very durable, because such posts are not attacked by insects and they do not deteriorate from exposure to moisture. The horizontal members are entirely above the ground and may be made of wood. However, in some instances it may be desirable to make the horizontal members of concrete.

It is an object of this invention to provide a fence having elements which are produced easily and inexpensively.

It is another object of the invention to provide a fence which can be easily assembled on the site.

It is another object of the invention to provide a fence which provides privacy by obscuring the view and reflecting sounds and yet permits the passing of breezes and light.

Other objects and advantages of my construction will become apparent as the specification proceeds to describe the invention with reference to the accompanying drawings, in which—

Fig. 1 is a top view of a portion of the fence in place;

Fig. 2 is sectional view taken on line 2—2 of Fig. 1 with the upper bars removed to more clearly show the post structure;

Fig. 3 is an enlarged sectional view taken on line 3—3 of Fig. 2 with all the bars in place.

Referring now to drawings, the intermediate posts 10 and the corner posts 12 are mounted vertically with a considerable portion extending below the ground level 14. The posts 10 have slots 16 extending inwardly from two opposite sides. The sides of the slots 16 diverge slightly outwardly toward the opposite sides of the post. The slots 16 are open at the inside face of the post, and they extend downwardly at an angle of approximately 20 degrees with respect to the vertical. It should be understood that this angle may be somewhat greater or less than 20 degrees if desired.

The corner posts 12 have slots 18 extending inwardly from adjacent sides. The sides of slots 18 diverge slightly outwardly. Each of the posts 12 has a recess 20 at its inner corner. Recess 20 has sides equal in width to the depth of the slots 18 to permit the horizontal bars 22 to be inserted in the slots 18 after the horizontal bars 24 are in place in slots 18. Interference between bars 22 and bars 24 is thus avoided.

Metal reinforcing rods or wires are cast in the posts 10 and 12. Bolts 26 are cast in posts 10 and bolts 28 are cast in corner posts 12. Bolts 26 and 28 are received in holes in top rails 30. Washers 32 are placed over the bolts 26 and 28. Nuts 34 are then threaded on the bolts 26 and 28 to engage the washers 32 and hold the top rails 30 against the tops of the posts 10 and 12.

A bar support 36 is secured to each top rail 30 by a

2

bolt 38. A curb 40 of concrete is poured along the length of the fence. The curb 40 supports the posts 10 and 12, and it secures the lower end of bar support 36. Bar support 36 engages the inner edges of bars 22 and 24 to prevent them from sagging or warping. It should be understood that although I prefer bar support 36 to be in form of channel shown, other structural shapes may be used. Bar support 36 also functions to hold the bars 22 and 24 in place in the slots 16 and 18 of the posts 10 and 12 respectively. The curb 40 provides an edge against which the grass can be moved thus avoiding the need for trimming the grass.

The lower edges of the bars 22 and 24 are in substantially the same horizontal plane with the upper edge of the bar immediately below so that the space enclosed by the fence cannot be viewed from the outside. The fence may be constructed to the height desired, and more or less than the five boards shown can be used.

Although I have shown a preferred embodiment of my invention, it is contemplated that various changes may be made without departing from the scope or spirit of my invention, and I therefore desire to be limited only by the claims.

I claim:

25. 1. A fence comprising intermediate posts substantially rectangular in cross-section and being provided with elongated slots extending inwardly from opposite sides, the elongated slots in said intermediate posts having open ends at the inside faces of said intermediate posts to 30 removably receive bars inserted into said inclined elongated slots and being inclined downwardly with respect to the inside faces of said intermediate posts, a corner post substantially rectangular in cross-section and being provided with a recess at the inner longitudinal corner, 35 said corner post being provided with downwardly inclined elongated slots extending inwardly from the sides adjacent the inner corner and having open ends in the recess to removably receive bars, a plurality of bars extending between said intermediate posts and said corner post and having their ends supported in the elongated slots of said corner post and said intermediate posts.

2. A fence comprising intermediate posts substantially rectangular in cross-section and having elongated slots extending inwardly from opposite sides, the elongated slots in said intermediate posts having open ends at the inside faces of said intermediate posts and being inclined downwardly with respect to the inside faces of said intermediate posts, a corner post substantially rectangular in cross-section and having a rectangular recess at the corner, said corner post having downwardly inclined elongated slots extending inwardly from the sides adjacent the inner corner and having open ends in the recess, a plurality of bars extending between said intermediate posts and said corner post and having their ends supported in the elongated slots of said corner post and said intermediate posts, rails extending between said intermediate posts and said corner posts, means securing said rails to the tops of said intermediate posts and said corner post, a curb receiving said intermediate and corner posts at the ground level, and bar support members secured to said rails and to said curb intermediate of said intermediate posts and said corner post to engage and support said bars.

3. A fence post substantially rectangular in cross-section and being provided with a V-shaped recess in one longitudinal corner of the post, and elongated slots rectangular in cross-section and extending downwardly and away from both sides of said V-shaped recess and being open to said V-shaped recess and to the adjacent sides of said post and being adapted to receive and support horizontal bars, said elongated slots having closed lower ends and upper ends opening into said recess, said slots

3

being arranged in pairs with the slots of each pair intersecting at said recess.
